UNITED STATES PATENT OFFICE.

FRANK CONRAD, OF PITTSBURGH, PENNSYLVANIA, ASSIGNOR TO WESTINGHOUSE ELECTRIC & MANUFACTURING COMPANY, A CORPORATION OF PENNSYLVANIA.

RECEIVING CIRCUIT FOR THE ELIMINATION OF STATIC DISTURBANCES.

Application filed October 17, 1918. Serial No. 258,530.

To all whom it may concern:

Be it known that I, FRANK CONRAD, a citizen of the United States, and a resident of Pittsburgh, in the county of Allegheny and 5 State of Pennsylvania, have invented a new and useful Improvement in Receiving Circuits for the Elimination of Static Disturbances, of which the following is a specification.

10 My invention relates to receiving circuits for use in connection with wireless apparatus, and it has for its object to provide simple and effective means whereby interference, particularly that known as "static," 15 may be largely eliminated, at the same time permitting the ready receipt of transmitted impulses.

The single figure of the accompanying drawing is a diagram of a wireless receiving 20 circuit embodying a preferred form of my invention.

In the wireless transmission of intelligence, it is well known that the receipt of transmitted impulses is frequently seriously disturbed 25 by static charges produced upon the antenna by the passage of wind thereover, these static charges flowing to ground through the receiving apparatus. Similarly, the passage of electrostatically charged clouds over 30 the antenna attracts or repels charges from the ground, these also passing through the receiving apparatus and confusing the operator.

I find that the static charges and static induction in antennæ of different heights is 35 substantially the same, whereas the intensity of the impulse set up in an antenna by incoming signals varies with the height, being much stronger for an antenna of considerable height than for one of moderate height. I make use of this phenomenon in 40 eliminating the disturbing effects of static electricity by employing two antennæ for the receipt of messages, these antennæ being 45 so associated with receiving apparatus that the substantially equal charges imparted thereto by static influences cancel each other within the receiving apparatus, thus being rendered imperceptible to the operator. The 50 unequal amounts of energy imparted to the antenna by incoming impulses fail to cancel each other and thus a residual effect is imparted in the receiving apparatus which may be amplified if desirable in order to render 55 it more clearly perceptible to the operator.

Referring to the drawing for a more detailed understanding of my invention, I show a relatively high wireless antenna at 1 and a relatively low antenna at 2. These antennæ are shown of the flat-top type but 60 it is to be understood that any antennæ of the open-circuit kind may be used. Some antennæ, usually in the form of a coil, act wholly, or at least largely, by the change in flux through them which is caused by an arriving ether wave. Other antennæ act wholly or mainly in virtue of the electrostatic changes which accompany such a wave. I have used the term open-circuit antenna herein to designate any form of antenna belonging in the latter class. A receiving transformer is shown at 3 and the antenna 1 is connected to one end of a primary winding 4 thereof, whereas the antenna 2 is connected to the other end thereof. An 65 adjustable tap 5 is provided at an intermediate point in the primary winding 4 and is grounded at 6. The secondary winding 7 of the transformer 3 is connected to a receiving circuit of usual form.

Assuming equal sizes for the two antennæ, the amounts of energy received therein are substantially equal with undesired static disturbances but are quite unequal with transmitted impulses, the high antenna developing much more energy in the latter case. The point of attachment 5 is, under these 70 conditions, placed at substantially the mid point of the winding 4, so that, with a given static impulse, the upwardly flowing current in the lower half of the winding 4 magnetically neutralizes the downwardly flowing current in the upper half of this winding, the current of both antennæ flowing to 75 ground through the tap 5 and the lead 6. As a result, with a static impulse, no flux is developed in the transformer 3, and consequently, no electromotive force is produced in the winding 7 and no effect is produced in the local receiving circuit.

Turning now to the effect upon the receipt of a transmitted impulse, the current flowing from the antenna 1 is much larger than that flowing from the antenna 2 and, therefore, the magnetomotive force developed in the lower half of the winding 4 is greater than that developed in the upper half thereof. As a consequence, flux is developed in the core of the transformer 3 which traverses 80 the secondary winding 7, setting up current 85 105 110

flow in the local receiving circuit. The arriving signal produces a greater effect on the antenna 1, not only because a higher antenna possesses a better receiving capacity, but 5 also because, being farther from roofs, trees and the like, it is more exposed to the action of the arriving wave.

It is obvious that the resultant impulse at the receiving instrument is considerably 10 weaker than would be the case were this apparatus connected to a single antenna, but any well-known type of amplifier may be employed to increase the magnitude of the signals so that they shall be readily audible.

15 While I have shown my invention in its preferred form, it will be obvious to those skilled in the art that it is susceptible of still other minor changes and modifications without departing from the spirit thereof 20 and I desire, therefore, that only such limitations shall be placed thereupon as are imposed by the prior art or are specifically set forth in the appended claims.

I claim as my invention:

25 1. In a wireless receiving circuit, the combination with two antennæ of different heights, of a common local receiving circuit differentially connected to said two antennæ and susceptible of adjustment so that the 30 energy received on one antenna from a static impulse cancels the energy received upon the other antenna, and so that similar cancellation is not effected with incoming transmitted impulses.

35 2. In a wireless receiving circuit, the combination with two antennæ of different heights, of a common receiving transformer

having its primary winding connected between said antennæ, a local receiving circuit dynamically interlinked therewith, and a 40 connection from an intermediate point in said transformer primary winding to ground, said point being so selected that the inductive effects of the current flow from the two antennæ mutually cancel upon the receipt of 45 a static impulse and fail to do so upon the receipt of a transmitted impulse.

3. In a wireless receiving circuit, the combination with two antennæ of different heights, of a common receiving transformer 50 having its primary winding connected between said antennæ, a local receiving circuit dynamically interlinked therewith, and an adjustable connection from an intermediate point in said transformer primary winding 55 to ground.

4. In radio signaling apparatus, an antenna system having associated portions arranged at different elevations but at substantially the same distance from the source of 60 signals to be received, and means for detecting signals including means for balancing out the effects of static disturbances.

5. In a signal receiving system, two adjacent flat-top antennæ of different height. 65

6. In a signal receiving system, two adjacent flat-top antennæ of different height and signal translating means controlled by the difference of energy between said antennæ. 70

In testimony whereof, I have hereunto subscribed my name this 25th day of Sept., 1918.

FRANK CONRAD.
